SYNCHRONOUS MOTOR DRIVEN CHIME
MOVEMENT FOR CLOCKS

Fritz Heckert, Schwenningen-on-the-Neckar,
Germany, assignor to Kienzle Uhrenfabriken
A. G., Schwenningen-on-the-Neckar, Germany,
a corporation of Germany

Application January 6, 1931, Serial No. 506,847
In Germany September 27, 1930

8 Claims. (Cl. 58—38)

This invention relates to an electrically operated striking or chime clock which is driven by a continuously rotating motor, in the present instance, preferably an A. C. synchronous motor. In clocks of this type it is customary to have the entire driven time gear train, or at least its driving means (spring or weight) continuously and permanently associated in driving relation with the driving motor by means of a gear drive. At the same time, however, during the striking operation, the normally non-connected striking trains must be mechanically coupled with said driving motor. For this purpose, in past practice, it has been customary to utilize shiftable, normally non-operative jaw couplings or clutches between the driving motor and the train and which are adapted to be engaged with and disengaged from the continuously rotating clock driving mechanism. As a modification, it has also been customary to arrange the first gear wheel of the arrested strike driving gear train as a sort of movably engageable or disengageable clutch, such as an axially displaceable gear adapted to be meshed or unmeshed with the continuously rotating members of the driving power by a suitable control means.

These previous arrangements, however, have the disadvantage that the above noted meshing or unmeshing or coupling actions cannot be set to coincide exactly with correct time periods, and a perceptible time period loss occurs in the striking action, the result being that the striking will be inaccurate.

In addition, such an arrangement when applied to household clocks has the particularly important disadvantage that the strike clutching or engaging and disengaging movements create an undesirable clashing noise.

In the present invention, in order to obviate these disadvantages, the driving wheels of the otherwise commonly arrested striking trains are so constructed as to be kept constantly in motion and remain continuously and positively coupled with the constantly driven time trains by means of suitable, intermediate constantly coupled planetary gear trains. The driving power is then transmitted by time gearing, in the well known manner, to the corresponding strike train by locking one of the rotating parts of the intermediate train for a given period. This locking is preferably performed by the striking ratchet mechanism or the dial hand motion operation of the constantly running time train.

Another advantage is that if the chime striking means should be out of step or time, the strike regulator will eventually be automatically reset to cause the chimes to be struck in proper sequence and time.

These and other capabilities will be apprehended as the herein description proceeds, and it

is obvious that modifications may be made in the device without avoiding the spirit hereof or the scope of the appended claims.

The accompanying drawings illustrate an embodiment of the invention as applied to a striking train clock driven by a synchronous electric motor, wherein

Fig. 1 is a front view of a time train, with part of the front plate of the movement being removed;

Fig. 2 illustrates a front view of the striking lever mechanism, the front movement plate being partially removed;

Fig. 3 depicts the front plate with details of the locking lever and action during the locking operation;

Fig. 4 is a fragmentary section, enlarged, taken on the line 4—4 of Fig. 1, looking in the direction of the arrow, showing the hour strike gear coupling;

Fig. 5 is a fragmentary section, enlarged, taken on the line 5—5 of Fig. 1, looking in the direction of the arrow, showing the quarter strike gear coupling;

Fig. 6 shows the strike regulating means, removed from position, and illustrates the action thereof on the quarter-past stroke when in correct position to strike the chimes.

Fig. 7 shows the same means but in incorrect position or partially out of time, when the chimes will not sound; and

Fig. 8 discloses the action of the quarter hour strike regulator with the cam out of time, but on the hour, at which setting the chimes will sound, and the cam permitted to run to reset to resume correct striking position.

Fig. 9 is a sectional view taken on line 9—9, Fig. 1, looking in the direction of the arrows; and Fig. 10 is a sectional view taken on line 10—10, Fig. 1, looking also in the direction of the arrows.

In Fig. 1, 1' indicates a continuously rotating synchronous motor of well known type having a driving pinion 1, used for driving the clock and which, by means of intermediate gears 2, 3 meshed to rotor pinion 1, as shown, is connected with the planetary train 4, 5, 6, Figs. 3 and 4, of the hour striking mechanism generally denoted by 7. As shown in Fig. 9, the gear 4 is rigidly attached to the accompanying bevel gear on the shaft 22, and on the hub of this bevel gear, as shown, is rigidly mounted a pinion 4'. This pinion is in mesh with the gear 8, rigid with which is a pinion 8', and the last mentioned pinion meshes with a gear 14. The gear 14 has on the opposite end of its shaft, as shown, a pinion 9, which meshes with a gear 10, and on this latter gear is a pinion 10' which meshes in driving relation with a gear 11, Fig. 10. Rigid with the shaft of the gear 11, as shown, is a pinion 11', 60

and this pinion meshes with a gear 12, to which is affixed a dial hand shaft 13.

The second gear and pinion train 8, 9 branches off in front of the intermediate train 2, 3 and is adapted, by means of the gear and pinion wheels 10, 11 to transmit power to drive the time train (the latter being provided with the dial hand shaft 13) and also by means of a gear 14 to transmit motion to a second planetary gear train 16, 17, 18 operating the quarter hour striking mechanism 19, Figs. 4 and 5.

It is obvious that as the motor 1' rotates, it will positively drive the driving gear and pinions 3, 4 and 10, 11 and 12 of the time train, and also 15 the planetary striking trains 7 and 19 of both the hour and quarter hour striking mechanisms.

The operating means in the present instance comprises a synchronous motor and hence requires no driving power, per se, such as a spring 20 or weight; and thus all of the time train up to and including the dial hand wheel 12 is positively coupled with the driving motor and hence runs continuously.

As long as the running clock is not striking, 25 both the hour and the quarter hour strike mechanism trains are at rest. This is accomplished by the use of the planetary gear trains 4, 5, 6 or 16, 17, 18, Figs. 4 and 5. Each train consists of two sun gears 4 and 6, and 16 and 18 and 30 planet gears 5 or 17. The latter gears are respectively rotatably mounted on vertical shafts 20 and 21 carried in turn by shaft 22 and 23. The two sun gears 4, 6 and 16, 18 are each rotatably journaled on shafts 22 and 23.

35 The driving sun gears 4 and 16 are in mesh with the continuously rotating gears 3 and 14 and hence rotate continuously. The driving sun gears 6 and 18 each have locking plates 24 and 25 and are adapted to be stopped thereby as indicated in Figs. 4 and 5. This construction causes the planet gears 5 and 17 to move around the stationary sun gears 6 and 18 and thus carry the shafts 22 and 23 along. Since each of these shafts is connected with the rest of its gear train, 45 the result is that when the sun gears 6 and 18 are locked, their gear trains will be set in motion.

The shaft 22 of the planetary gear train 4, 5, 6 of the hour striking mechanism 7 carries on 50 its free end Figs. 3 and 4, and in front of the front movement plate A, the actuator 26 of the well known snail arrangement 27, 28, 29. The rear end of the shaft 22 carries the striking cam 30 of the hour hammer operator 31.

55 A locking member is provided for the planetary gear train 4, 5, 6, of the hour striking mechanism 7 in the form of a pawl 33, (Fig. 2) pivoted on shaft 32, and which is retracted by spring 34 and prevented from dropping into the locking ratchet teeth on wheel 24.

60 The other end 36 of said pawl 33 is bent at right angles and operates in the path of a pivoted angular locking lever 38 loosely pivoted on the pin 37 and which lever has an extension 39 provided with a resiliently pivoted blocking ratchet abutment 40.

65 The other extension 41 of the lever 38 is biased by spring 42 to cause its angularly turned end 44 to bear constantly upon the periphery of a disk 43, having a notched portion 44. In addition, a carrier stud or pin 45 on the locking lever arm 41 rests upon the well known drop-in lever 27 of the rack arrangement 28, 29 so that 75 the locking lever 38 is really supported by the

drop-in lever 27 (Fig. 3) loosely pivoted on the pin 37.

Between the hour release lever 46 and the locking lever 38 there is disposed a transmitting lever 47 which is arranged to bear under the arm 41 of the locking lever 38 and to lift the same by means of pin 48.

On the shaft 23 of the intermediate gear train 16, 17, 18 of the quarter hour strike train 19 Figs. 2 and 5, there is fastened an actuating disc 50 provided with four notch portions of progressively increasing distances apart and of the well known type.

A jumper disc 51 is provided to cooperate with said locking disc 50, the two being resiliently connected together in the well known manner. The shaft 23 in addition carries (in front of the front movement plate A) an hour release cam 52 while the rear end of the shaft 23 carries the driving wheel 53' for operating the striking arrangement 54 and the hammers 55, as in Figs. 1 and 5.

A locking pawl 57, which is pivoted at 56 (Fig. 2) serves as a locking member for the intermediate train 16, 17, 18, said locking pawl being prevented from engaging its end 59 into notches of the locking disk 25 by a spring 58. The other bent end 60 of said pawl protrudes into the path of arm 61 of a three armed locking lever 63, which is rotatably journaled on 62. The arm 61 also carries at this point a unilaterally blocking ratchet abutment 66. The second arm 64' of the locking lever 63 rests against the actuating plate 50 or periodically on the jumper plate 51 and falls into a notch 49 whenever it is not hindered from doing so by the jumper plate 51. The third arm 65 of the locking lever 63 cooperates with the bent end of a transmitting lever 67, as at Fig. 5, shown dotted and in full lines to indicate approximate position, which is lifted at every strike release period by the release lever 68, 69 and release snail 70, as in Figs. 6, 7, 8.

The train of the quarter striking mechanism is controlled to operate in the following manner:

Before each strike release period the release snail 70 lifts the locking lever 63 through the intermediary of the release lever 68, 69 and the transmitting lever 67 until the release lever 68 has reached the highest point of the corresponding extension or tooth of the release snail 70, Figs. 6, 7 and 8. During this rotation of the locking lever 63 the unilaterally blocking ratchet abutment 66 strikes with its edge 71 (Fig. 2) against the bent over end 60 of the locking pawl 57 and is rotated around its pivot 57 to such a degree that it slides off the arm 60 (Fig. 2) whereupon it falls back to its abutment position under the urge of spring 73. At the proper instant of the striking release period the release lever 68 drops from the release snail 60 tooth, so that the release lever 68, the transmission lever 67 and finally also the locking lever 63 will be pulled back instantly by the action of the spring 73. Thereupon the abutment 66 engages with its oblique surface 75 against the bent over end 60 of the locking pawl 57 and forces this against the action of the spring 58 so far back that the other end of the locking pawl engages into the locking rack plate 25 (Fig. 2). The driven sun wheel 18 is therefore instantly locked without time loss. The planet wheel 17 rolls upon it and thereby turns the shaft 23 together with the portions of the quarter striking train carried by it.

The number of quarter strokes is controlled 7

in the well known manner by the locking disc 50, since the arm 64' of the locking lever 63 reaches the next notch of the locking disc and drops into it. During this act of dropping-into-the-notches, the arm 61 of the locking lever rotates just a slight additional amount so that the abutment 66 slides off the bent over end 60 of the locking lever. The locking pawl 57 is pulled out of its locking position by the action of the spring 58. The driven sun wheel 18 is thus set free without time loss, while simultaneously the shaft 23 together with the planet wheel rotating on the same axis is locked by the locking disc 50.

The gear train 4, 5, 6 of the hour striking mechanism operates in an entirely similar manner. After the last 4/4 or hour stroke the hour release lever 46 is lifted by the raised cam surface of the hour release cam 52. The free end of the lever 46 is laterally turned as shown, and when this lever is raised, said end engages under and raises the lever 27. At the same time the locking lever 38, 39 is raised by the transmission lever 47 until the unilaterally blocking ratchet abutment 40 has been led past the bent over end 36 of the locking lever 33.

At the instant of the hour strike release period the hour release lever 46 drops into the low portion of the hour release disk 52 and at the same time the transmission lever 47 drops back into its starting position.

The locking lever 41 rests with its pin 45 upon the lifted drop-in lever 27 and by this movement it has, with the oblique surface portion, as 77, of its abutment pawl 40 displaced the locking lever 33 in the manner already pointed out and against the urge of spring 34 to such an extent that it locks the toothed wheel 24 of the intermediate train 4, 5, 6. The driven sun wheel 6 is thus locked without time loss, the planet wheel 5 rolls over it, and drives the shaft 22 with the actuator 26 and the hour hammer lifting cam 30.

The resistance of the striking hammer and its spring and other mechanism driven by the shaft 22 is sufficient to keep these parts stationary after the parts 43, 44 are unlocked before lever 33 engages with the teeth of the wheel 24.

The number of hour strokes is determined in the well known manner by the notches of the rack 28 in combination with the hour snail 29. At the last stroke, that is, when the rack 28 is in its highest position, the dropping lever 27 drops below the lower end of the rack 28. This lower position of the drop-in lever 27 suffices to allow the arm 41 of the locking lever 38 still to remain seated completely on the periphery of the notched disk 43. This arm 41 then is caught by the notch 44 and falls into it. During this drop the locking lever 39 is displaced an additional amount so that the abutment pawl 40 slides off the locking lever 36 and releases the same. This sets the locking disk 24 and the driven sun wheel 6 is instantly set free without time loss, while the shaft 22, together with the planet wheel 5 rotating on the same axis, is instantly locked.

The advantages of employing a mechanism as described will be apparent, if it is considered that the synchronous clock motor, a type most generally used for the operation of clocks, is very sensitive to overloads.

It is known that such a motor will come to rest if the load demands a torque which is greater than the maximum load. The load carried by a synchronous clock motor is small, hence

the difficulties in preventing an overload when the chime striking train is clutched into the time train.

That this difficulty has been overcome in the present invention, may be explained as follows:

It is a known fact that a force required to move a body out of a condition of rest, is much greater than that, to accelerate the speed of a moving body. Therefore the stationary gears of the chime striking train when clutched into the time train require a greater force than if rotating. While stationary however, a certain force is required to rotate the masses of gears 6 and 24 Fig. 4. As soon as these gears are locked however, that much more force will now be available to overcome the inertia of shaft 22 and its gears, to afterward operate the chime striking train.

After this train has come to a stop again, the force released on the time train is now switched over in part to move gears 6 and 24 out of a condition of rest.

Therefore the differential gear trains as employed, serve the purpose to always retain a certain reserve in force, during a period of overcoming the dead inertia of stationary mass, and thus make the clock more reliable in its operation.

It demands less of a load on the motor, as has been proven by experiment.

A further advantage of employing differentials instead of conventional clutch mechanism is to be found in the fact that the clutch parts constitute additional masses and therefore increase the inertia to be overcome when starting the chime striking train. Besides this the clutch parts are quite often connected with springs required for the release of the parts. These springs most generally cause a pressure and through this a frictional resistance on the clutch parts which would still more increase a resistance against the rotation of the chime striking train.

A special arrangement must be provided for automatically regulating the striking in case the striking means of the clock has become deranged for any reason whatever, so that, for example, the quarter hour strike does not coincide with the time shown. This strike regulating arrangement, as in Figs. 6, 7 and 8, consists of a regulating lever 82, 83 which is associated with the transmission lever 67 at point 64, one arm of said regulating lever being adapted to rest on a pin 80 of the hour release cam 52. The other end 82 of the lever serves as an abutment or for the release lever 68, 69, which by means of the regulating lever 82, 83 lifts the transmission lever 67. During the 4/4 strike the arm 83 is left without support on disk 52 owing to the omission of a fourth pin (similar to 80). If, however, in this position, owing to some derangement in the clockwork, one of the 1/4, 2/4, or 3/4 cams of the release cam 70 happens to lift the release lever 68, then the arm 83 will rise freely without operating the transmission lever 67. The stroke is therefore not released. It is only when, as in Fig. 8, the long 4/4 cam 81 lifts arm 69 so high that said arm 69 directly touches the transmission lever 67 and lifts it an additional distance that the transmission lever releases the strike, which will then coincide with the time indicated.

It is obvious that, by this arrangement, a striking mechanism is provided which, when it has become deranged, will reset itself correctly within one hour.

It is evident from the foregoing that in the arrangement of the invention as described the drive of the striking works is derived from the continuously rotating motor without requiring any disengageable gear or clutch arrangement, or consequent loss of time needed to shift such clutch. All of the gearing of the time and strike are trains constantly in positive engagement with the driving motor. Hence it is not possible for any train to get out of operative phase relation with respect to the other or the motive means.

Likewise, the use of planetary gearing as a coupling means obviates the usual clutch noise incident to the operation of throwing a corresponding clutch train into action.

It will further be noted that the control of the entire striking mechanism is effected by a system of simple, reliable operating levers.

20 In the following claims the three principal devices of the chime clock described shall be referred to as (1) time train, (2) chimes-strike control mechanism, and (3) hour striking mechanism.

25 The time train relates to the motor and the gearing for the rotation of the dial hands and gears 4, 4' and 16 of the two differentials 4, 5, 6 and 16, 17, 18.

The control mechanism relates to the hourly and $\frac{1}{4}$ hourly chime controls connected with differentials to the time train and comprising cam and lever devices which regulate the operation of the striking mechanism.

The striking mechanism relates to the striking arrangement 54, hammers, chimes and similar parts.

Having thus described my invention, what I claim is:

1. In combination, a time gear-train; a time indicator driven by the train; a strike mechanism; a differential having an idler element, a motive element fast with a gear of the train, and an active element connected to drive the strike mechanism when the idler element is stationary; and means for at times locking said idler element for causing the striking.

2. In combination, a time gear-train; a time indicator driven by the train; a strike mechanism; a differential having an idler element, a motive element driven by a gear of the train, and an active element connected to drive the strike mechanism when the idler element is stationary; and means to at times lock said idler element for causing the striking, and to release the idler element at other times to allow the strike mechanism to rest.

3. In combination, a time gear-train; a time indicator driven by the train; a strike mechanism; a differential having an idler element, a motive element fast with a gear of the train, and an active element connected to drive the strike mechanism when the idler element is stationary; and means controlled by the time train for at times locking said idler element for causing the striking, and for releasing the idler element at other times to allow the strike mechanism to rest.

4. In combination, a single synchronous electric motor; a time gear-train driven thereby; a time indicator driven by the train at a speed of constant ratio to the speed of the rotor; a strike mechanism of relatively small inertia; a differential having an idler element, a motive element fast with a gear of the train, and an active element connected to drive the strike

mechanism when the idler element is stationary; and means for at times locking said idler element for causing the striking, and to release the idler element at other times to allow the strike mechanism to rest.

5. In combination, a single synchronous electric motor; a time gear-train driven thereby; a time indicator driven by the train; a strike mechanism of relatively small inertia; a differential having an idler element, a motive element fast with a gear of the train, and an active element connected to drive the strike mechanism when the idler element is stationary; and means for at times locking said idler element for causing the striking, and to release the idler element at other times to allow the strike mechanism to rest; the normal rotation of the whole time train, the active and idler elements, and the motor providing momentum to overcome the inertia of the strike mechanism when the latter starts.

6. In combination, a single synchronous electric motor; a time gear-train driven thereby; a time indicator driven by the train; a strike mechanism of relatively small inertia; a differential having an idler element, a motive element fast with a gear of the train, and an active element connected to drive the strike mechanism when the idler element is stationary; means for at times locking said idler element for causing the striking, and to release the idler element at other times to allow the strike mechanism to rest; the normal rotation of the whole time train, and the active and idler elements providing momentum to overcome the inertia of the strike mechanism when the latter starts; the time indicator being at all times driven by the motor while the motor rotates at a constant ratio to the speed of the rotor.

7. In combination, a single synchronous motor; a time gear-train driven thereby; a time indicator driven by the train; an hour strike shaft carrying a cam; a striking arm actuated by said cam; an hour-strike differential having an idler element, a motive element fast with a gear of the train remote from the motor, and an intermediate element engaged between the other two elements and mounted on the hour-strike shaft; means controlled by said train for locking said idler element for causing the hour striking, and to release the idler element at other times to allow the strike shaft to rest; the normal rotation of the whole time train, and the intermediate element and idler element providing momentum to overcome the inertia of the strike shaft when the latter starts, the latter offering relatively small inertia against starting.

8. In combination, a single synchronous motor; a time gear-train driven thereby; a time indicator driven by the train; a quarter-hour strike mechanism; a quarter-hour-strike differential having an idler, a motive element fast with a gear of the train near the time indicator, and an intermediate element engaged between the idler and element and connected to the quarter-hour-strike mechanism; means controlled by said train for locking said idler for causing the quarter-hour striking, and to release the idler at other times to allow said mechanism to rest; the normal rotation of the whole time train, and the intermediate element and idler providing momentum to overcome the inertia of the strike mechanism when it starts, the latter affording relatively small inertia against starting.
